UNITED STATES PATENT OFFICE.

MAX HOURVITCH, OF FOREST CITY, PENNSYLVANIA.

TRUNK.

SPECIFICATION forming part of Letters Patent No. 651,189, dated June 5, 1900.

Application filed February 19, 1900, Serial No. 5,865. (No model.)

To all whom it may concern:

Be it known that I, MAX HOURVITCH, a citizen of the United States of America, residing at Forest City, in the county of Susquehanna and State of Pennsylvania, have invented certain new and useful Improvements in Trunks, of which the following is a specification.

My invention relates to an improvement in trunks, and more particularly to that class of trunks which is designed for use by commercial travelers, traveling salesmen, &c., for displaying their samples or goods to possible customers.

Very often a salesman will enter a store with his samples and will have no convenient or adequate place in which to exhibit them to the buyer. In such an instance they have to pile their samples one on top of the other in any available space, which practice soon removes the original appearance and shape, causing them to look shop-worn and lessens their attractiveness. It also inconveniences the salesman to a great degree by getting the samples out of order, and the buyer is delayed in selecting the goods he desires to purchase, thus consuming what is often valuable time in the making of a sale. Again, the samples may be placed in out-of-the-way corners and where they are liable to be overlooked when it becomes necessary to collect them and left behind, causing the salesman a great deal of annoyance and loss of time and money to replace the lost samples. To obviate all these disagreeable circumstances, I have devised a trunk within the lid of which are contained folding devices which when set up afford a most desirable and convenient support upon which to display goods or samples, and at the completion of a sale the samples may be packed neatly in the trunk, the display-shelves folded into the lid, and the whole device carried to the next stopping-place.

It consists, further, of certain novel features of construction and combinations of parts, which will be more fully described hereinafter and particularly pointed out in the claims.

In the accompanying drawings, Figure 1 is a perspective view of my device, showing the display-shelves in raised position to receive the samples or goods to be displayed. Figs. 2, 3, and 4 are sectional views through the lid of the trunk, showing the shelves folded

and stowed away for traveling, as well as the details thereof.

A represents the body of the trunk, and B 55 is the lid or cover thereof, suitably fastened to the body of the trunk by hinges or other means. The entire trunk is made strongly and provided with slats or strips on its exterior surface, affording additional strength. 60

To the outside of the cover B and at either end thereof is secured by a pivot 2 a leg or support 1, said leg or support being preferably flat on its inner face to afford a bearing-surface against the side of the lid, which prevents 65 play or movement thereof. These pivots 2 are placed as near the upper edge of the lid when open as is convenient in order that the upper end 3 of the leg may not project above the top of the trunk when the lid is closed. 70 A securing means 4 is also provided on these legs, which means may consist of a set-screw, thumb-screw, or other suitable means, which is inserted in the side of the body of the trunk when closed, thus affording an additional fastening, as well as serving to strengthen and relieve the sides from exterior pressure. When the lid is opened, the legs are revolved on their pivots and the fastening means inserted in the side of the cover. This affords 75 80 a support for the lid or cover when open and goods are being displayed.

CD are the shelves, which are made in sections, of which shelf C has, preferably, five and shelf D three. A single support 5 is 85 hinged or otherwise fastened in one corner of the lid, with its face against the side thereof to avoid play, as at 6, so that it will fold into the cover or lid of the trunk. On the outer side or face of this support or standard 5 an 90 eyelet 7 is placed, for a purpose presently to be described. In the opposite corner and similarly fastened is a like support 8, provided with an eyelet 9 upon its outer face. Shelf C is constructed as follows: The central section 10 is hinged or otherwise secured at 11 to the upper end or face of the support 8 and on the outer face thereof. At each end of the section, which is just long enough to fit into the cover of the trunk, are hinged shorter sections 12 and 13, the hinges of which are so arranged that when the sections are opened to present a flat surface their adjacent ends abut each other. On the under side of the

larger section 10 of the shelf a hook or other suitable supporting means 14 is secured, as at 15. When not in use, this hook is placed under the catch 16 at the end of section 10, 5 and thus held out of the way. When, however, it is desired to set up the shelf, the hook is detached from the catch and inserted in the aforementioned eyelet 9 in the outer face of the support 8, and thus aids in supporting 10 the outer end of section 10 of the shelf. Section 13 has secured to it a like section 17, provided with a similar catch and hook for engagement with the eyelet 7 on support 5, and this section 17 is likewise provided with a section 18, hinged thereto in like manner as the 15 rest.

On the upper side of section 17 is a bolt 19, sliding in keepers 20, secured to the section in any suitable manner. This bolt is provided 20 with a projection 21 at one end for operating it, and its other end is received in a socket 22 on section 13. It will be seen by this arrangement that the two sections 13 and 17 may be fastened together and made as firm and rigid 25 as though they were composed of one piece. The bolt being revoluble in its keepers and socket admits of the projection being turned flat on the section, thus preventing any interference with the exhibits.

30 Straps 23, secured in the bottom of the lid at 24 and equipped with the usual buckles, are provided to retain the shelves in place in their folded position in the lid.

It is not thought necessary to enter into a 35 detailed account of the construction of shelf D, which is in general similar to shelf C. It has the supports 25 and 26, similarly constructed and situated in the other two corners of the lid and provided with eyelets 27 and 28; 40 but these standards are longer than those of shelf C, and thus raise shelf D to a higher plane. This shelf is composed of but three sections 29, 30, and 31 of approximately-equal length and just long enough to fit neatly in the lid 45 or cover of the trunk. Support 25 has hinged to its upper end the section 29, provided with a hook 32 and catch 33. To section 29 is hinged section 30 in like manner as in shelf C and upon which a bolt 34 is secured by keepers 50 35. Section 30 in turn has hinged thereto section 31, likewise provided with a hook 36 and catch 37 for its support. Section 31 is also provided with socket 38 for the reception of bolt 34.

55 The operation of this device may be gathered from the foregoing in connection with the drawings; but to recapitulate: When the salesman desires to display his goods, he loosens the set-screws or other securing 60 means which fasten the legs on each side of the trunk and swings the legs on their pivots, fastening the screws in the lid of the trunk, thus securing the legs tightly in place. He

then opens the lid and allows it to descend until it is in a horizontal position, when the 65 legs will rest upon the floor. The shelves will now be disclosed neatly and compactly folded in the lid and strapped down to prevent any displacement thereof. He unbuckles the straps and raises section 17 of 70 shelf C, which draws with it sections 18, 13, and 10. After raising to a sufficient height he pushes the connected sections to the right, whereupon support 8 will rise. He then holds the shelf in a raised position with one 75 hand, while with the other he places support 5 in a perpendicular position. Then after shooting bolt 19 into its socket he rests the extended shelf on the single support 5, and detaching the hooks from their catches, places 80 them in the eyelets on the supports and straightens the shelf, which is now ready for the reception of the samples. To return the shelves to a folded position in the lid, a reversal of this process only is necessary. 85

It is evident that slight changes might be made in the form and arrangement of the several parts described without departing from the spirit and scope of my invention, and hence I do not wish to limit myself to 90 the exact construction herein set forth; but,

Having thus described my invention, what I claim as new, and desire to secure by Letters Patent, is—

1. The combination, in a trunk, of a lid, 95 shelves hinged together and wholly contained within said lid when folded, but capable of extension, and pivotal supports for holding the lid in a horizontal position, said supports also acting as a locking means for the trunk. 100

2. The combination, in a trunk, of a lid, pivoted supports for said lid, said supports also constituting a locking means for the trunk, hinged shelves folding into the lid, 105 said shelves capable of being raised and extended, and hinged supports for the shelves.

3. The combination with a trunk, and a lid, of legs pivoted to the lid for the support thereof when in an open position, said legs provided with means whereby they are securely 110 attachable to the body of the trunk as an aid in locking the same, hinged shelves contained within said lid and capable of being raised and extended, hinged supports for said shelves 115 and straps for retaining the shelves and supports in a compact position when folded.

In testimony whereof I have signed my name to this specification in the presence of two subscribing witnesses.

his
MAX X HOURVITCH.
